UNITED STATES PATENT OFFICE.

FREDERICK S. GLINES, OF LYNN, MASSACHUSETTS, ASSIGNOR TO LORENZ MUTHER, OF NEWTON, MASSACHUSETTS.

MACHINE FOR APPLYING ADHESIVE.

1,341,311.

Specification of Letters Patent.

Patented May 25, 1920.

Application filed November 28, 1917. Serial No. 204,460.

To all whom it may concern:

Be it known that I, FREDERICK S. GLINES, a citizen of the United States, residing at Lynn, in the county of Essex and State of Massachusetts, have invented a new and useful Improvement in Machines for Applying Adhesive, of which the following is a specification, reference being had therein to the accompanying drawings.

10 This invention relates to machines for applying adhesive and more especially to a machine of that character which is designed to apply an adhesive in spots.

One object of my invention is to provide 15 a machine for applying adhesive which is efficient, rapid and clean.

Another object is to provide a machine 20 which is small, compact and cheap in construction and simple and effective in operation.

Still another object is to provide means whereby the working parts of my machine 25 may be readily cleaned.

Other objects will be in part obvious and 30 in part pointed out hereinafter.

In the accompanying drawings wherem 35 is illustrated one of the various possible embodiments of my invention, Figure 1 is a front elevation, with parts broken away, of a machine constructed and operated in accordance with my invention; Fig. 2 is a plan view of said machine; Fig. 3 is a section taken along line 3—3 in Fig. 2 looking from left to right; and Fig. 4 is an illustration of 40 a piece of material, in this case part of a shoe lining, to which adhesive has been applied in accordance with my invention.

Referring now more particularly to the 45 drawings which illustrate the preferred embodiment of my invention, there is indicated at 10 a base upon which is mounted a reservoir 11, restrained against lateral movement by lugs 12, adapted to contain a supply of paste or other adhesive, and which is provided with a cover 13 extending over the greater portion of the top of the reservoir. Said cover may also serve as a table or support for the material to which the adhesive is to be applied. At 14 is shown a spring 50 catch secured to the cover 13 and adapted to frictionally engage one wall of the reservoir for the purpose of retaining said cover in operative position.

One corner of the base 10 is extended and

carries a pair of upstanding ears or lugs 15, 55 each of which has threaded therein a cone-pointed screw 16 which is checked against loosening by a lock-nut 17. At 18 there is a bearing having seats adapted to engage the cone-points of the screws 16 forming a supporting bearing locating part 18 with reference to the other parts of my machine and allowing said part to be revolved about an axis passing through screws 16 for a purpose to be described later. Cast on the base 60 10 is an upwardly extending ear or lug 19 having a hole adapted to receive a pin 20, which may be passed through two corresponding holes in opposite sides of the part 18 in order to firmly lock the bearing piece 70 in operative position.

Mounted for rotation in the bearing piece 18 are two substantially parallel shafts 21 and 22. Shaft 22 extends to the left and within the reservoir 11 as shown in Fig. 1. 75 Mounted in said shaft are a number of paste applying members 23 (see Fig. 3), comprising a disk or circular plate having radially projecting arms or fingers 24 arranged at suitable intervals about its periphery. Collars 25 serve to separate the paste applying members which, together with the collars are firmly retained on the shaft 22 by a washer 26 and a screw or nut 27 or other suitable means. The disks carrying the 80 fingers 24 are preferably arranged so that the fingers 24 are in a staggered relation.

While I have represented the paste applying element of my machine as being made up of disks and collars, it is to be understood that said element is not limited to the particular construction shown but may be constructed in any suitable manner, as, for instance, a drum having suitable pins inserted therein, or may even be made from 90 one solid piece.

Referring to the shaft 21, which is substantially parallel to shaft 22, there is mounted on said shaft 21 a series of disks 28, of suitable form, for frictionally engaging 100 and feeding the material to which the paste is to be applied. Said disks are separated or spaced by collars 29 and the disks and collars are firmly retained upon the shaft 21 by a washer 30 and screw or nut 31 or other 105 suitable means. The edges of the disks 28 may be serrated or coated with any suitable material to increase the friction with which

they engage the material to which adhesive is to be applied. On the bearing piece 18 and secured thereto by means of screws 32, is shown a piece 33 extending substantially 5 parallel to shaft 21 and adjacent to the feeding disks 28 in such a manner as to form a guard about said disks.

Adjacent the right-hand end of the bearing piece 18, as shown in Fig. 1, are two 10 gears 34 and 35 respectively fastened to shafts 21 and 22. Adjacent gear 34 is shown a pair of grooved pulleys 36 and 37, of which 36 is an idler loose upon the main shaft 21, and 37 is secured to said shaft to 15 transmit power to the shaft 21 and through the gears 34 and 35 to shaft 22. The idler is retained in its position on shaft 21 by washer 38 and screw 39 or other suitable means.

20 In Fig. 3 at 40 is shown a bar having fastened thereon at suitable intervals, projecting fingers 41, which are arranged between the paste applying members, as shown in Figs. 2 and 3, to form a guard which acts 25 to prevent the material from becoming entangled with the various parts of the mechanism after the adhesive has been applied, and also serves to assist in the separation of the material from the paste applying fingers.

30 Fig. 4 is an illustration of part of a shoe lining 42 as it appears after having the adhesive 43 applied to it by my machine. It is to be understood that the size, shape and 35 arrangement of the spots of adhesive is not limited to that shown in the illustration.

In the operation of my machine, assuming that the reservoir contains a proper amount of adhesive, that the parts are thoroughly 40 clean and that power has been applied to the pulley 37, the material to which it is desired to apply the adhesive is placed upon the cover 13 and moved thereon toward the paste applying and feeding elements; when the material comes into engagement with said elements, the feeding disks act upon the material to feed it forward, and, at the same time, to hold it in contact with the paste applying fingers 24 45 which in their revolution, transfer the adhesive from the reservoir to the material in spots. The material as it emerges from between the feeding and pasting means passes over the guard fingers 41 and is delivered ready for use.

50 It is possible to use my machine in such a manner as to apply adhesive to a portion of the surface only. It will be noticed that on the left hand side of the illustrated embodiment of my invention, referring to Fig. 1, there is no obstruction to prevent the material from extending outwardly to the left from between the feeding disks and the paste applying fingers. This is an advantage 55 because it enables the operator to so ar-

range the work that only a portion will be coated, the uncoated portion extending to the left from between the feeding disks and the paste applying fingers. By retaining hold of the material the operator can direct 70 its course through the machine in a straight line and thereby avoid any twisting of the material which might be due to the fact that it was fed by a portion only. In cases where it is desired to coat only a portion of 75 a shoe part, for instance, the construction of my machine has special advantages.

If it should be desired at any time to clean the paste applying and feeding elements, the pin 20 is withdrawn from engagement with the lug 19, the cover 13 removed, and the bearing piece and mechanism supported thereby is revolved on the cone-pointed screws 16 as a center until the elements are nearly in a vertical position 85 and all the parts out of the reservoir are accessible.

90 It is to be observed that my machine is of extreme simplicity both in construction and operation. In addition it is of such form of 95 construction that the material being treated is absolutely protected from injury from dirt or adhesive. The right side of the material is always uppermost as it passes through the machine and is engaged by the 100 peripheries only of the feed wheels. These are arranged in a staggered relation with the paste or adhesive applying disks and therefore are not liable to take on the adhesive from the latter.

105 It is to be understood that my invention is not to be limited to the precise construction herein shown and described, as it may be embodied in many other forms within the purview of my invention. Therefore I desire to claim the invention broadly except where specifically limited in the following claims.

110 What I claim is:—

115 1. A machine for applying adhesive comprising a base, a bearing pivotally mounted on said base normally in engagement with said base but capable of rotation around said pivot point, rotatable means for applying adhesive to the material and means for feeding said material, both said adhesive applying means and said feeding means being each mounted at one end thereof in said bearing.

120 2. A machine for applying adhesive comprising a reservoir adapted to contain a supply of adhesive, a bearing pivotally mounted adjacent to said reservoir, two shafts carried by said bearing and rotatably mounted therein, one of said shafts carrying a plurality of paste applying members and the other of said shafts carrying a plurality of feeding members, both of said shafts being supported at one end only in said bearing.

125 3. A machine for applying adhesive hav- 130

ing, in combination, a base, a bearing pivotally mounted on said base normally in engagement with said base but capable of rotation around said pivot point, a reservoir 5 for the adhesive, rotatable means carried by said bearing for transferring the adhesive from said receptacle to the material to be coated and means for feeding said material forward in engagement with said rotatable 10 means, said feeding means being supported in said bearing at one end only leaving an open space between the other end of said feeding means and said rotatable means through which the material to be coated may 15 extend.

4. A machine for applying adhesive having, in combination, a reservoir adapted to contain a supply of adhesive, a bearing pivotally mounted adjacent said reservoir, rotatable means mounted at one end in said bearing for transferring the adhesive from said reservoir to the material to be coated and a shaft carrying a plurality of feeding members, said shaft being supported at one 25 end only in said bearing.

5. A machine for applying adhesive having, in combination, a reservoir adapted to contain a supply of adhesive, a bearing pivotally mounted adjacent said reservoir, a 30 rotatable member mounted in said reservoir with one end supported in said bearing and provided with a plurality of radial fingers for transferring the adhesive to the material to be coated and means for holding said 35 material in engagement with said adhesive applying fingers and for feeding the material forward, said holding and feeding means being supported at one end only in said bearing.

6. A machine for applying adhesive comprising a reservoir for the adhesive, a bearing pivotally mounted adjacent said reservoir, two shafts each supported at one end thereof and rotatably mounted in said bearing, one of said shafts carrying a plurality of disks having radial fingers and the other 45

of said shafts having mounted thereon a plurality of feeding disks.

7. A machine for applying adhesive having, in combination, a reservoir for the adhesive, a bearing pivotally mounted adjacent said reservoir, means carried by said bearing for applying adhesive in spots to the material to be coated and means for feeding said material forward, said feeding means 50 comprising a shaft rotatably mounted in said bearing at one end only and provided with a plurality of feeding disks, which are spaced apart by a plurality of collars, one collar being interposed between every two 55 feeding disks.

8. A machine for applying adhesive having, in combination, a base, a bearing pivotally mounted on said base and normally in engagement therewith but capable of rotation around said pivot, a reservoir for the adhesive, two shafts each mounted at one end thereof in said bearing one above the other, a plurality of disks having radial fingers for applying adhesive in spots to the 60 material to be coated mounted on the lower of said shafts, and a plurality of disks for feeding the material mounted on said upper shaft, the space between the free ends of said shafts being unobstructed to permit the 65 material to extend beyond the ends of said shafts.

9. A machine for applying adhesive having, in combination, a reservoir for the adhesive, a bearing pivotally mounted adjacent said reservoir, means carried by said bearing for applying adhesive to sheet material and means for feeding said material forward; said feeding means comprising a shaft rotatably mounted at one end in said 70 bearing, a plurality of disks secured at intervals on said shaft and a plurality of collars mounted on said shaft for spacing said 75 disks.

In witness whereof I hereunto set my hand 80 this seventeenth day of November, 1917.

FREDERICK S. GLINES.
